UNITED STATES PATENT OFFICE.

FRANK A. JOHNSON, OF AURORA, AND JOHN AHLGREN, OF BATAVIA, ILLINOIS.

INTAKE-MANIFOLD ATTACHMENT.

Application filed March 17, 1923. Serial No. 625,806.

To all whom it may concern:

Be it known that we, FRANK A. JOHNSON and JOHN AHLGREN, citizens of the United States, residing at (1) Aurora, (2) Batavia, in the county of Kane and State of Illinois, have invented certain new and useful Improvements in an Intake-Manifold Attachment, of which the following is a specification.

10 This invention relates to attachments for internal combustion engines and the primary object of the invention is to provide a novel device adapted to be inserted in the intake manifold for insuring the correct 15 breaking up of the combustible mixture and the correct commingling of the constituents thereof, prior to the entrance of the mixture into the engine cylinders, thereby insure the correct operation of the engine.

20 Another object of the invention is the provision of a body formed of a spirally wound wire disposed in the entrance conduit to the manifold through which the gas and air from the carburetor is adapted 25 to be sucked, the convolutions of the coil tending to spread further apart, according to the amount of suction of the engine pistons, the passage of the gas and air between the convolutions tending to break up the gas 30 and air into small molecules and effectively commingle the gas and air together to form the correct combustible charge.

35 A further object of the invention is to provide novel means for mounting the attachment within the manifold, so as to permit the holding thereof in correct position without displacement.

40 With these and other objects in view, the invention consists in the novel construction, arrangement and formation of parts as will be hereinafter more specifically described, claimed and illustrated in the accompanying drawings, forming a part of this specification, in which drawings:

45 Figure 1 is a longitudinal section through a portion of an intake manifold showing the improved attachment incorporated therewith, parts of the attachment being shown in section.

50 Figure 2 is a detail transverse section taken through the attachment on the line 2—2 of Figure 1 looking in the direction of the arrow.

55 Referring to the drawings in detail, wherein similar reference characters designate corresponding parts throughout the

several views, the letter A generally indicates an intake manifold, B the upper end of a carburetor connected therewith and C the improved charge refining attachment. 60

The manifold A can be of any preferred type or construction and includes the depending body portion 5 and the upper outwardly extending arms 6 which lead to the intake ports of the cylinders. The lower 65 end of the body portion 5 of the intake manifold A is provided with an outwardly extending annular flange 7 which is adapted to normally abut the outwardly extending annular flange 8, formed on the upper 70 outlet end of a carburetor. The carburetor indicated by the reference character B can be of any preferred type or character.

The improved attachment C comprises a 75 body 10 formed of wire wound spirally to provide a plurality of convolutions 11, all of which are of substantially the same diameter. These convolutions 11 normally fit relatively close to one another, and owing to the inherent resiliency of the material from which the body is formed, the coils will automatically spread, when a suction is formed in the intake manifold 6 by the operation of the pistons of the engine. It is preferred to have the wire from which 80 the body 10 is formed of a substantial semi-cylindrical shape in cross section, so as to provide a flat outer face 12 and a semi-cylindrical inner face 13. This construction provides sharp edges which are adapted 85 to be disposed in intimate relation, which forms means for atomizing or breaking up the gas and air into minute molecules and for permitting the thorough commingling thereof. It is obvious that the space between 90 each pair of convolutions 11 will act as a nozzle for permitting the flow of the charge from the attachment. 95

In order to hold the body 10 in correct 100 axial relation to the body portion 5 of the manifold A, the lowermost coils or convolutions of the body are spread out or unwound as at 14 so as to assume a conical shape and are disposed between a pair of frusto-conical flanges 15 and 16 formed on 105 the annular clamping plates 17 and 18. A suitable packing gasket 19 is disposed between the plates 17 and 18, and the plates 17 and 18 and the gasket 19 are placed 110 between the abutting flanges 7 and 8 of the body portion 5 and carburetor B. Suitable bolts or the like 20 are utilized for

holding the flanges 7 and 8 together and to bring the plates 17 and 18 toward one another. It is obvious that the flanges 15 and 16 will tightly engage the coils or convolutions 14 and thus hold the attachment C in correct position.

An inverted conical-shaped cap 25 formed of metal is provided for the upper end of the body 10, and this conical-shaped body 19 can be provided with an attaching flange 26 which can be secured in any preferred manner to the uppermost convolutions 11. This inverted conical-shaped body 25 can be provided with minute slots 27 through 15 which the charge is also adapted to escape.

The attachment is adapted to absorb some heat from the engine and thus the charge passes through the convolutions thereof, the same will become heated to a certain extent 20 which will tend to vaporize the charge.

From the foregoing description, it can be seen that an exceptionally simple and durable attachment has been provided for internal combustion engines, which will insure 25 the correct commingling of the gas and air prior to the entrance thereof to the cylinders of the engine and the breaking up of the charge into minute particles.

Changes in details may be made without 20 departing from the spirit or the scope of this invention.

What we claim as new is:—

1. In combination, a carburetor, a manifold, a charge refining attachment disposed 35 between the carburetor and intake manifold including a coiled body having the convolutions thereof of the same diameter disposed in relative close proximity to one another, and an inverted conical-shaped cap secured 40 to the outermost convolution of the body provided with a plurality of minute outlet slots.

2. In an internal combustion engine, the combination, an intake manifold, a carburetor, an attachment for the engine clamed 45 between the carburetor and intake manifold including a body formed from a coiled wire disposed in axial relation to the outlet port of the manifold, the convolutions being disposed in close proximity to one another and of the same diameter, an inverted conical-

shaped cap carried by the outermost convolution, a base flange formed on the cap engaging the outermost convolution, the cap having a plurality of minute outlet slots 55 formed therein.

3. In an internal combustion engine, the combination with an intake manifold, a carburetor and a charge refining attachment for the engine disposed in the intake manifold including a body formed from a coiled wire, the convolutions of the body being of the same diameter and disposed in close proximity to one another, a cap carried by the upper end of the body, and a pair of clamping members disposed between the manifold and carburetor for engaging and holding the lower end of the body therebetween to prevent accidental displacement thereof.

4. In an internal combustion engine, the combination, an intake manifold, a carburetor, a charge refining attachment for the internal combustion engine including a body formed from a coiled wire having the convolutions thereof of the same diameter and disposed in close proximity to one another, an inverted conical-shaped cap carried by the body, a pair of clamping plates disposed between the manifold and the carburetor, 75 frusto-conical shaped flanges formed on the inner edge of said clamping plates for receiving the inner end of the coiled body.

5. As a new article of manufacture, a charge refining device for an internal combustion engine comprising a spirally wound body of substantially the same diameter throughout its entire length, a cap carried by the outer end of the body, a pair of clamping plates, compression gaskets disposed between the plates, means for bringing the plates toward each other, and frusto-conical shaped flanges formed on the inner edges of the plates for receiving the inner end of said coiled body.

In testimony whereof we affix our signatures in presence of two witnesses.

FRANK A. JOHNSON.
JOHN AHLGREN.
